STABILIZING RUDDER

Filed Nov. 3, 1928

Inventor:
Frank Rebl

UNITED STATES PATENT OFFICE

FRANK REBL, OF RAVEN ROCK, NEW JERSEY

STABILIZING RUDDER

Application filed November 3, 1928. Serial No. 317,034.

The object of this invention is to provide simple and effective means for permitting small power boats to ride evenly and steadily over the surface of ordinarily rough water 5 unperturbed by the waves.

Another object of the invention is to provide lateral stabilizing fins attached to the rudder of the boat in such a manner that the maximum power delivered to the water by 10 the propeller is exerted thereon so as to steady the boat as well as to prevent the stern of the boat from being depressed due to suction.

A still further object of this invention is to provide lateral stabilizing fins which are 15 adjustable as to forward inclination so as to permit a maximum efficiency to be attained regardless of the type of boat said stabilizing apparatus is used upon.

A still further object of the invention is to 20 provide vertical stabilizing fins located approximately amid-ships of the boat, one at each side, so as to prevent skidding when making a sharp turn.

My invention is clearly illustrated in the 25 annexed drawings in which similar characters of reference refer to similar parts throughout the several views.

Figure 1 is a longitudinal elevation of the boat.

30 Figure 2 is a rear view of the rudder showing the lateral stabilizer.

Figure 3 is a cross-sectional view of Figure 1 on the line 4—4.

Referring to the drawings, Figure 5 represents the hull of the usual small speed boat 35 which is driven forward by means of the propeller shaft 6 and propeller 7. The boat is steered by means of the rudder 8 attached to the rudder post 9 in the usual manner, the 40 rudder post being capable of turning in the bearing struts 10. 11 represents the tiller rod which is grasped by the hand or other means in steering the boat. Attached to the vertical rudder 8 by means of bolts 12 are laterally projecting fins 13. These fins 13 are 45 capable of a slight forward or rearward inclination as will be readily understood owing to the slots 14 in the rudder. In operation it should be readily understood that ordinarily, without the lateral stabilizing fins,

the stern of the boat will "sit down" in the water causing the boat to eventually pop up and down with each wave, incidentally retarding the speed to a considerable extent. With the use of these lateral stabilizing fins, the 55 stern of the boat is buoyed up due to the hydroplane effect thereof, effectively preventing the aforementioned objections. In addition, these stabilizing fins permit the boat to make a "hair-pin" turn as, when the boat banks 60 during the circling movement, the stabilizing fins will also prevent the boat from turning over. It will be noticed that the fins project from the rudder at a slight upward angle so as to obtain the maximum resistance to turning over when making a sharp turn. To prevent the boat skidding and to provide better control, a pair of vertical fins 15 are attached to each side of the boat approximately in the 65 center thereof.

Having thus described my invention I claim as new and wish to secure by Letters Patent:

1. A motor-boat rudder provided with lateral planes on either side thereof, the outer 75 extremities of said planes being inclined upwardly from the rudder.

2. A motor-boat rudder provided with lateral planes on either side, the rudder being provided with vertical slots, and means on 80 the planes for adjustably clamping said planes to the rudder.

Signed at New York, in the county of Bronx and State of New York this 2d day of November, A. D. 1928.

FRANK REBL.
